CLAIM

The ornamental design for an LED light tube, as shown and described.

DESCRIPTION

FIG. 1 is a first perspective view of a LED light tube showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The broken lines shown in the drawings depict portions of the LED light tube that form no part of the claimed design. The additional short-dash-long-dash broken lines surrounding the enlargement areas in FIGS. 1, 2, 9, and 10 are for annotative purposes only and form no part of the claimed design.
